UNITED STATES PATENT OFFICE.

HERMAN A. UNKE, OF CLEVELAND, OHIO.

PIPE-THREAD PROTECTOR.

Application filed January 17, 1925. Serial No. 3,047.

This invention relates to devices for protecting the threads of pipes and other articles while being coated and also while being transported and handled.

5 It is one of the objects of the invention to provide a thread protector that will be simple in construction, comparatively inexpensive to manufacture and which may be securely and quickly applied to the threads 10 and also readily removed therefrom. It is a further object of the invention to provide a protector that will be securely held in position and will also serve as a closure for the end of a pipe to exclude water and other 15 foreign materials therefrom.

The invention has for a further object the provision of a thread protector adapted for use in the manufacture of electrical conduit for the purpose of protecting the 20 threads from the enamel or coating material during the enameling operation, the protector having the advantage that it may be left on the conduit for the purpose of protecting the threads during transportation, 25 or the protector may be removed and reused.

Other objects of the invention and the features of novelty will be apparent from the following description taken in connection 30 with the accompanying drawings, of which:

Figure 1 is an end elevation of a thread protector embodying my invention;

Fig. 2 is a longitudinal section through the same, the protector being shown in position 35 on the threads of a pipe;

Fig. 3 is a view similar to Fig. 1 but showing a slightly different form of the invention;

Fig. 4 is a view similar to Fig. 2 but 40 showing the form of the invention illustrated in Fig. 3; and

Fig. 5 is a plan view of one of the parts of the protector.

Referring to the drawings 10 indicates 45 an ordinary pipe having the usual tapered threads 11 on the end thereof. In order to preserve the threads 11 in perfect condition, during transportation and handling, I provide a protector which, in the form illustrated in Fig. 2, comprises a cup-shaped member 12 having a flange or ring-shaped portion 13, of frusto-conical form, the taper of the flange 13 conforming substantially to the taper of the threads 11. The end wall 50 of the member 12 is embossed as shown best in Fig. 2 and aligned openings 14 extend

through this portion for the purpose of receiving a wrench 15, which may be in the form of a short length of rod. The member 12 is preferably formed of sheet metal by 60 stamping operations.

As will be seen from Fig. 2, the flange 13 is of slightly larger internal diameter than the outside diameter of the threads 11 and in the space thus provided there is arranged 65 the flange 16 of a cup-shaped retainer member that is made of relatively soft fibrous material such as a tough paper stock. I prefer to use a paper stock that has good frictional qualities so that when the member 70, 12 is driven over the flange 16 it will be securely wedged and held thereon, at the same time causing the threads to be mashed into the flange 16, as shown in Fig. 2. The end wall 17, of this retainer, also serves as 75 a closure for the end of the pipe to exclude water and other foreign material therefrom and thus preserve the interior of the pipe in good condition until it reaches the point where the pipe is to be used. When the 80 protector is to be removed the wrench 15 is inserted and the protector and paper retainer are screwed off from the end of the pipe.

In applying the protector to the end of 85 the pipe the retainer is first placed in the position shown in Fig. 2 and the member 12 is then driven on over the retainer by a mallet or other device, thereby making this a very simple and inexpensive operation. 90

The retainer for the member 12 may be made in different ways but I have devised a very simple and inexpensive form that has numerous advantages from the standpoint of taking up only a small amount of space 95 when being stored or transported and is relatively free from liability of becoming mutilated before use. This form of retainer is illustrated in Fig. 5 and consists of a disk 18 having several wings 19 projecting from the periphery thereof and adapted to be folded at right angles to the plane of the disk 18 and, when thus folded, to constitute a substantially continuous ring which serves as the flange 16, above described. I form 100 this retainer by stamping it from paper stock, by means of a suitably shaped punch and, in order to facilitate bending of the wings 19 a crease 20 may be provided in the disk 18 adjacent its periphery. These 105 retainers will, of course, be made in different sizes to suit the different sizes of pipe and 110

in applying the retainer the disk 18 is held against the end of the pipe and the member 12 is then pressed against the wings 19, the pressure folding the wings against the threads and permitting the member 12 to be driven to the position shown in Fig. 2.

The form of the invention illustrated in Figs. 3 and 4 is, generally, similar to that illustrated in Figs. 1 and 2 with the exception that instead of embossing the end wall of the member 12, a suitably shaped opening 21 is formed therein to receive a wrench by means of which the protector may be unscrewed from the pipe. The opening 21 in the periphery has the further advantage of permitting the insertion of a hook 22 for the purpose of lifting the pipe when it reaches the point of use. In this case the end wall 17 of the retainer which, in Fig. 5, is the disk 18, is punctured by the hook 22 or any other suitable device, thereby permitting the hook to be positioned as shown. This is an especially desirable feature in the case of pipes of large size which must be handled by means of cranes or derricks or other powerful lifting apparatus.

While I have shown and described my thread protector in connection with the threads on the end of a pipe, it is obvious that it is adapted to protect the threads on a rod or any other article and it will therefore be understood that the invention is not limited to the particular form, shown and described, but includes all forms of application that come within the scope of the appended claims.

Having thus described my invention, what I claim is:

1. In a device of the class described, the combination of an article having a tapered threaded end, a cup-shaped cap having a continuous frusto-conical wall adapted to surround said threaded end and the taper of which conforms substantially to the taper of said end, and a cup-shaped member of relatively soft material interposed between said cap and said threaded end and into which the threads are mashed when the cap is forced onto said threaded end.
2. In a device of the class described, the combination of an article having a threaded portion, a cup-shaped protector adapted to surround said threaded portion, and a cup-shaped member of relatively soft material interposed between the threads and said protector and the protector being of such size the threads are mashed into said material when said protector is forced into position to protect said threads.
3. In a device of the class described, the combination of a pipe having a threaded end, a cup-shaped member of relatively soft material adapted to be arranged on said threaded end, and a separate metallic cup-shaped member adapted to be driven endwise

over the first-mentioned member and of such size in relation to the latter as to cause the threads to be mashed into said material.

4. In a device of the class described, the combination of a pipe having a threaded end, a cup-shaped member of relatively soft material adapted to be arranged on said threaded end, and a separate metallic cup-shaped member adapted to be driven endwise over the first-mentioned member and of such size in relation to the latter as to cause the threads to be mashed into said material and the first-mentioned member having an end wall which forms a closure for the end of the pipe.

5. In a device of the class described, the combination of a pipe having a threaded end, a protector adapted to surround the threads of said end, and a cup-shaped member separate from said protector and made of relatively soft material, said member being arranged between said threads and said protector and the protector being of such size that the threads are mashed into said material when the protector is forced onto the end of the pipe, the end wall of said member serving as a closure for the end of the pipe to exclude water and foreign material therefrom.

6. In a device of the class described, the combination of a pipe having a tapered threaded end, a cup-shaped protector for the threads of said end having an axially extending flange of frusto-conical form the taper of which conforms substantially to the taper of said threaded end, the end wall of said protector being provided with means with which a wrench is adapted to cooperate in unscrewing the protector from the end of the pipe, and a layer of relatively soft material arranged between said threads and said flange and into which the threads are mashed by driving said protector over said material when the latter is in position on the end of the pipe.

7. In a device of the class described, the combination of a pipe having a tapered threaded end, a cup-shaped protector for the threads of said end having an axially extending flange of frusto-conical form the taper of which conforms substantially to the taper of said threaded end, the end wall of said protector being provided with means with which a wrench is adapted to cooperate in unscrewing the protector from the end of the pipe, and a cup-shaped member of relatively soft material arranged between said threads and said flange and into which the threads are mashed when the protector is driven on to the end of the pipe, the end wall of said member serving as a closure for the end of the pipe.

8. In a device of the class described, the combination of a pipe having a threaded end, a protector for the threads of said end

comprising a ring surrounding the threads and adapted to be forced endwise thereover, and a cup-shaped member of relatively soft fibrous material having an axially extending flange arranged between said threads and said ring and having the threads mashed thereinto by driving the ring thereover, the end wall of said member normally serving as a closure for the end of the pipe and 10 being adapted to be readily punctured, as and for the purposes described.

9. In a device of the class described, the combination of an article having a threaded end, a protector for the threads of said end 15 comprising a ring surrounding the threads and adapted to be driven endwise thereover, and a retainer for said protector consisting of a circular member made of relatively soft fibrous material having wings projecting 20 from its periphery adapted to be bent substantially at right angles to the disk to form a cup-shaped member, said wings being positioned between said threads and said ring and having the threads mashed into 25 them when the ring is forced into position thereover.

10. In a device of the class described, the combination of a pipe having a tapered

threaded end, a protector for the threads of said end comprising a ring surrounding the threads and conforming substantially to the taper thereof, and a retainer for said protector consisting of a disk of relatively soft fibrous material having wings projecting from its periphery adapted to be bent substantially at right angles to the disk to form a cup-shaped member, said wings being positioned between said threads and said ring and having the threads mashed into them when the ring is forced into position and said disk serving as a closure for the end of the pipe to exclude water and foreign material therefrom.

11. In a device of the class described, the combination of a threaded member and a protector for the threads of said member comprising a circular member made of paper and having a plurality of wings adapted to surround said threads with their adjacent edges in abutting relation, and a metallic 50 cup having a frusto-conical flange adapted to be driven over said member into wedging relation to said wings and cause said threads to be mashed into said wings.

In testimony whereof I affix my signature.
HERMAN A. UNKE.
